US0D1038991S

(12) **United States Design Patent** (10) Patent No.: **US D1,038,991 S**
(45) Date of Patent: ** Aug. 13, 2024

(54) **DISPLAY SCREEN OR PORTION THEREOF
WITH ICON**

- (71) Applicant: **Apple Inc.**, Cupertino, CA (US)
(72) Inventors: **Jesse Boettcher**, San Jose, CA (US);
Anton Davyдов, Gilroy, CA (US)
(73) Assignee: **Apple Inc.**, Cupertino, CA (US)
(**) Term: **15 Years**
(21) Appl. No.: **29/850,634**
(22) Filed: **Aug. 22, 2022**

(57)

CLAIM

The ornamental design for a display screen or portion thereof with icon, as shown and described.

DESCRIPTION

The FIGURE is a front view of a display screen or portion thereof with icon showing the claimed design.

The broken lines in the FIGURE show a display screen or portion thereof, and form no part of the claimed design.

1 Claim, 1 Drawing Sheet

See application file for complete search history.
